UNITED STATES PATENT OFFICE.

PAUL GERHARDT, OF CHICAGO, ILLINOIS.

BUILDING CONSTRUCTION.

1,243,281

Specification of Letters Patent. Patented Oct. 16, 1917.

Application filed April 17, 1916. Serial No. 91,536.

To all whom it may concern:

Be it known that I, PAUL GERHARDT, a citizen of the United States, residing at Chicago, in the county of Cook and State of Illinois, have invented a certain new and useful Improvement in Building Construction, of which the following is a full, clear, concise, and exact description, reference being had to the accompanying drawings, forming a part of this specification.

The advent of the comparatively modern factory system founded upon division of labor has instituted a new phase of building development involving a number of novel problems in building construction and imposed new conditions which had to be met.

The increased value of real estate has compelled adoption of the multi-story building. This has solved the problem of gathering a great number of workers within such range of each other that the full value of the scheme of division of labor can be realized at a maximum efficiency.

For intensive activities one of the most difficult but most important considerations is that of illumination. Whereas heretofore the transparent roof sufficed to illuminate the entire area of a single story building, the multi-story building cannot be thus treated since illumination is effective only for the upper floor. Furthermore, the placing of windows at various points about the sides of a building has become inadequate because of adjacent multi-story buildings. The requirement for adequate natural illumination has become acute, both because of the cost of artificial illumination and the injurious effect upon the eyesight, and also because many such operations require natural light to show true color value. The multi-story building presents such great advantages that it has persisted in spite of difficulties of illumination and the like. But demand for good light and good ventilation has been very marked and especially so in buildings constructed for housing business activities, such as manufacturing plants, offices, salesrooms, etc., where large areas are devoted to intensive activities requiring favorable conditions for efficient conduct of operation.

The latest step in building construction is the employment of reinforced concrete for forming the frame and floors of the building. The ease and speed of construction and

the small cost of labor required to perform the various operations, together with the generally fireproof character of the structure, has compelled a very wide adoption of this type of construction.

60

My invention aims to provide a building construction of the multi-story type having a maximum area for illumination and ventilation and capable of being carried out particularly in a reinforced concrete construction.

I shall now describe my invention with the aid of the accompanying figures in such terms as will enable one skilled in the art to practise the invention. In the accompanying drawings...

70

Fig. 1 is a perspective of a building constructed in accordance with my invention;

75

Fig. 2 is a diagram illustrating the admission of light to the inside of the structure in accordance with the prior art;

Fig. 3 is a similar diagram illustrating the action of light in entering a building constructed in accordance with my invention;

80

Fig. 4 is a plan view of one end of the building shown in Fig. 1;

85

Fig. 5 is a similar plan view of a modification;

Fig. 6 is an isometric fragmentary view showing the manner in which the column, floor and spandrel are formed in one integral construction;

90

Fig. 7 is an elevational view showing the spandrel and floor in section;

95

Fig. 8 is a plan view taken from below showing the structure of Fig. 7;

100

Fig. 9 is a view similar to Fig. 7 showing a plurality of floors in sections;

Fig. 10 is a similar view of a modification in which the spandrel is placed away from the column;

105

Fig. 11 is a similar view in which the spandrel is removed from the column and the space between column and spandrel filled with concrete;

110

Fig. 12 is similar view showing a larger filling between the column and the spandrel; and

115

Fig. 13 illustrates another modification in which the spandrel is dispensed with and the line of sash is made continuous past the floor.

120

The building shown in Fig. 1 is characterized by a large percentage of the area being made up of glass. The building is

125

of the reinforced concrete construction throughout, this type of construction being fireproof and permanent in addition to the quality of lending itself readily to rapid and high grade construction. In carrying out my invention I place the supporting columns for the floors back of the line of sash so that the extreme outer periphery of the building is transparent. It is to be understood of course that the architectural requirement of beauty of outline and of design compel in general a structure which has the appearance of solidity and permanence and this requirement is largely contrary to a design which would embody my invention to the greatest degree. But I wish it to be understood that in fulfilling the prerequisite of architectural design and to this extent departing from a condition of maximum efficiency for light transmission and ventilation, I do not intend to depart from my invention, but merely to adapt the same to a given set of conditions.

The structure that is essentially characteristic of the chief feature of my invention is the placing of the supporting column back of the line of sash, particularly in a multi-story building.

The building shown in Fig. 1 has seven floor levels which have floors formed in the shape of slabs. These slabs are formed of reinforced concrete in such manner that no floor beams are employed. The floor slabs are supported by a number of round posts 1 suitably spaced on the interior of the building, other posts 2 along the edges of the floors back of the sash 3 which form a part or all of the outer surface of the building along the sides. In the structure shown in Figs. 1 and 4, suitable piers, such as shown at 4, 5 and 6, may be employed to enhance the beauty of the building, while serving at the same time the function of supporting the load of that portion of the floor. Suitable corner posts or piers 7 are similarly employed, more particularly to define the lines of the building.

These piers and corner posts rest upon the foundation of the building. The outer edges of the floors are supported between the posts 2 and the piers 4, 5, 6 and 7 by means of the spandrels 8 which are formed integral therewith. As shown in Figs. 6, 7 and 8, the floor member 10 which is formed as a reinforced concrete slab is provided with the depressed panel 11 above the cap 12 of the column portion 13 which supports the particular section of floor. It is to be understood that suitable forms are constructed into which the concrete is poured so that these parts are formed substantially at one operation. The spandrel 8 is reinforced in the manner indicated in Fig. 7. The spandrel and the column are tied together by suitable diagonal

reinforcing rods 25 which join the column and the spandrel together. These rods 25 connect with the reinforcing members 26 which are embedded in the body of the spandrel 8. The body of the column portion 13 is reinforced by diagonal rods 27 which pass diagonally through the column cap 12 and connect with the floor slab 10. The column portion 14 projects into the side of the spandrel for a short distance in order to secure room for reinforcement between the spandrel and the portion 14 of the column. The top face of the spandrel is provided with a projecting ridge 15 which forms a sill. This sill is undercut as shown in Figs. 6 and 7 to define a drip edge which prevents rain, moisture and the like from defacing the outer face of the spandrel 8. The sash 3 is placed substantially on the center line of the spandrel 8 and is thus spaced away from the columns so as to permit light and air to pass therebetween.

It can be seen that the edges of the floors are supported from behind the sash instead of being supported by posts or pilasters in line with the sash and forming an exterior surface of the building as has previously been the practice. The edges in front of the columns are thus free of any supporting posts in front of the columns.

In Fig. 10 I have shown a construction wherein the spandrel 8 is spaced away from the column portion 14 to leave a clear space therebetween. This arrangement provides for more room between the sash and the column. In Fig. 11 I have shown the spandrel 8 as connected to the column portion 14 by a filling 17 which permits of reinforcing rods being passed from the spandrel to the column. A bracket or console 18 may be employed to connect the spandrel with the column portion 13.

Fig. 12 shows a similar arrangement except that the filling portion 17' as well as the bracket or console portion 18' are made of the width of the column. In the construction shown in Fig. 13 I have dispensed with the spandrels. In this form of construction the sash 3 is carried on past the floor so as to present a continuous front of glass. The sash 3 is supported at the floor by means of a suitable support 21 such as an angle iron or the like, that is fastened by inserts into the body of the concrete floor member 10.

It is apparent that the greater the percentage of transparent material, that is sash, employed, the less resistance will there be to the passage of light to the interior of the building. Placing of the supporting column back of the line of sash provides a structure which possesses sufficient strength to make possible the additional inflow of light without sacrificing to any material extent the efficient disposition of the mate-

rial. This can readily be seen from the diagram of Figs. 2 and 3. In Fig. 2 the columns 21, 22 and 23 are placed exactly in line with the sash 24. Now considering the space between columns 21 to 23 inclusive, it can be seen that the rays of light illustrated by lines at the right of Figs. 2 and 3 are able to pass into the building only between the posts. The rays which strike the columns themselves strike an opaque portion which in general would be of poor reflecting power and this light would in general be lost. A certain amount of the light which strikes the glass of the sash does not pass therethrough, but is reflected as is indicated by the dotted lines in the figures. Thus, out of the total spacing distance d the light can enter the building only through the space s while the space w which is taken up by the width of the column or posts is opaque and hence not useful for the transmission of light.

Considering the diagram of Fig. 3, it can be seen that all the light which strikes the glass surface, strikes a transparent medium and the amount of light that enters the building is greater than in the construction illustrated by Fig. 2. That is to say, the entire distance d which represents the pitch of the columns becomes available for the transmission of light. The light that strikes the post shown in Fig. 3 is not lost to the same extent that it is in Fig. 2, for the reason that even if the outer surfaces of these posts reflected the rays directly, the reflection from the interior of the glass would remain within the building. It is readily demonstrable mathematically that a greater amount of light will reach the interior of the building when constructed in accordance with the diagram of Fig. 3 than is constructed in accordance with diagram of Fig. 2.

The same state of facts prevails with respect to ventilation. That is to say, by placing the line of sash in front of the column, greater freedom of ventilation will be secured through the sash.

There are a number of incidental advantages in the type of construction which I have described. The extensive use of sash saves finishing the front or exterior of that part of the building. Inasmuch as the manufacture of sash is standardized and sash can be obtained conveniently in lots of any required amount in the open market, this type of construction lends itself to quick and inexpensive construction of buildings. The construction described lends itself readily to large scale operations as standard parts or standard forms may be employed throughout the building.

There is practically no interior finishing with respect to the sash as framing is not required and even if framing were employed,

the amount would be relatively very small. The sash that is employed may be of any desired type.

What I claim is:

1. In combination a reinforced concrete column having a cap formed integral therewith, a reinforced concrete floor slab integral with the cap, said floor slab having its front edge in front of the cap and the column, reinforced concrete piers formed integral with the edge of the floor upon each side of the column, said piers resting upon the foundation and being substantially flush with the building line, a reinforced concrete spandrel formed integral with the piers and the edge of the floor slab, a second column based upon the floor slab above the first column and being formed integral with the floor slab, a cap formed integral with the top of the second column, a second floor slab based on said second cap and formed integral therewith, said second floor slab being joined to and integral with the piers which piers extend between said floors, a second spandrel integral with said piers and said second floor slab and a run of sash between said spandrels running in an unbroken line from pier to pier lying in front of and being continuous past said second column.

2. In combination, a column having a cap, a floor slab resting upon said cap, a second column based upon said floor slab above said first column, a spandrel extending across the edge of said floor slab and in front of said columns and secured to said second column and a line of sash above and below said spandrel, said columns being situated adjacent the edge of the floor and being wholly behind the sash, said sash lying in front of and being continuous past said columns.

3. In combination, a column having a cap, a floor slab resting upon said cap, a second column based upon said floor slab above said first column, a spandrel extending across the edge of said floor slab and in front of said column, said spandrel comprising a beam for supporting the edge of the floor slab and a line of sash above and below said spandrel, said columns lying back of said sash adjacent to and supporting the edge of said floor slab, said sash being continuous past said columns.

4. In a building, a plurality of piers resting upon the foundation and lying substantially flush with the building line, a plurality of floors extending transverse to said piers, a plurality of spandrels joining said piers, said spandrels extending flush with said piers and being joined to and forming the outer edges of said floors, columns between said floors, said columns being placed adjacent the edges of the floors back of said spandrels, said columns being joined to the corresponding spandrels to support the same.

- laterally, and lines of sash extending between said piers and joining said spandrels, said sash lying in a plane in front of said columns and being continuous past said 5 columns.
5. In a reinforced concrete structure, a floor slab, a column supporting the outer edge of said floor slab, said column having an enlarged cap upon which the floor slab 10 rests, a column above said floor slab, and substantially in vertical line with said first column, a spandrel cast or formed integrally with said second column and said floor slab, said spandrel lying in a plane outside of the 15 columns, and a line of sash connected to the top and to the bottom of said spandrel, said spandrel having a wide upper edge forming a windowsill, said sill having an under cut edge.
- 20 6. In a reinforced concrete structure a floor slab, a column below said slab supporting the outer edge of the same, a column above said slab, said columns lying back of the edge of the floor slab, a spandrel joined 25 to the outer edge of said floor slab and lying outside of the columns, longitudinal reinforcing rods embedded in said spandrel, and transverse reinforcing rods embedded in said spandrel and in the body of the column 30 above said floor, said spandrel being adapted to support above and below it a line of sash forming an outside wall of the building, said sash being continuous in front of and past said columns.
- 35 7. In combination, a plurality of floor slabs, a plurality of supporting columns between said floor slabs, said columns being placed adjacent the edges of said floor slabs and forming the sole supporting means be- 40 tween floors for the adjacent edges of the floor slabs, and window sash at each floor level, said sash being in front of and continuous past the column at each floor level.
8. In combination, a reinforced concrete 45 floor slab, a reinforced concrete column adjacent the edge of said slab, and supporting said floor slab, said column forming the sole support for the edge of said slab in front of said column, a second reinforced column
- in alignment with said first column and adjacent the edge of said slab, and window sash lying in front of and being continuous past both of said columns.
9. In combination, a floor slab, a column adjacent to but back of the edge of said slab and supporting said slab, a column above said floor slab and in alignment with said first column, a second floor slab supported by said second column, window sash supported at its upper edge by said second slab and supported at its lower edge by said first floor slab, said sash lying in front of said second column, and other window sash supported in line with said first mentioned sash below said first floor slab and in front 60 of said first column, said second column constituting the sole supporting means between said floors for the edge of the second slab in front of the column.
10. In combination, a plurality of super- 70 posed floors, columns between said floors for supporting the edges of said floors, said columns being adjacent to but back of the edges of said floors, and window sash connected above and below to said floors and lying in 75 a straight run at the edges of the same, said window sash being continuous past said columns, the edges of the floors being disconnected from each other except through said columns.
11. In a building the combination of a plurality of floors, spandrels secured to the edges of said floors, supporting piers between said floors, said piers being flush with said spandrels, said piers and spandrels 85 forming the only exposed part of a side wall of the building, window sash forming a continuous uninterrupted front between said piers, said sash being secured at each floor to the spandrels above and below it, and 90 columns between floors, said columns being set in close proximity to the edges of said floors in such position as to support the floor edges but being back of the sash at each floor.
- 95 In witness whereof, I hereunto subscribe my name this 15th day of April, A. D. 1916.
- PAUL GERHARDT.
